STEPHEN BAZIN AND JAMES A. BAZIN, OF CANTON, MASSACHUSETTS.

Letters Patent No. 70,685, dated November 12, 1867.

IMPROVEMENTS IN MACHINERY FOR LAYING AND TWISTING ROPE.

The Schedule referred to in these Letters Patent and making part of the same.

TO ALL WHOM IT MAY CONCERN:

Be it known that we, STEPHEN BAZIN and JAMES A. BAZIN, of Canton, in the county of Norfolk, and State of Massachusetts, have invented certain Improvements in Machinery for Laying and Twisting Rope, of which the following is a full, clear, and exact description, reference being had to the accompanying drawings, making part of this specification, in which—

Figure 1 is a plan of our improved machine.

Figure 2 is a side elevation of the same.

Figure 3 is a section on the line $z-z$ of fig. 1.

Figures 4 and 5, details to be referred to.

Our invention relates to that class of machines for laying and twisting rope for which Letters Patent of the United States were granted to us on the 28th day of February, 1844, and on the 25th day of April, 1854. In the former patent a straight crane is described as being employed for guiding the rope as it was wound upon the winding-reel, but as the end of the crane traversed the arc of a circle, the rope, when at either end of the reel, was drawn at such an angle that it could not be wound with regularity, while, when at the centre, the coils were liable to ride upon each other, thereby causing delay and inconvenience. We afterward employed a curved crane, having an angular arm hinged thereto, as described in our aforesaid patent of 1854, so as to cause the rope to be fed in a direction parallel with the axis of the winding-reel. But although this device answered a good purpose, yet it did not fully accomplish the desired end, and the jointed crane was complicated and expensive.

Our present invention has for its object to overcome entirely the above-mentioned difficulties, and consists in the employment, in connection with a crane, of a guide-wheel or pulley, which slides on a horizontal rod or shaft parallel with the axis of the winding-reel, the rope passing from the end of the crane over the sliding-guide pulley, and thence to the winding-reel, by which means it is guided accurately, as required to form a perfect coil.

Our invention also consists in an improved device for insuring the regular and equal delivery of the strands.

In our aforesaid patent of 1844, each strand was passed once around a "rag"-wheel, these "rag"-wheels being each provided with a cog-wheel which engaged with a central cog-wheel so as to secure their simultaneous revolution. The strands, however, were liable to slip upon these "rag"-wheels as soon as they became worn, thus causing an unequal delivery of the yarn. To overcome this difficulty we pass each strand several times around a smooth roll or cylinder, so as to prevent its slipping thereon, the rolls being provided with gears, which engage with a central gear to insure their simultaneous revolution, and a "fleeter" or ring provided with an incline or inclines being applied to each roll to keep the coils in their proper position, and prevent them from riding up on each other.

To enable others skilled in the art to understand and use our invention, we will proceed to describe the manner in which we have carried it out.

In the said drawings, A is the base of the machine, from which rises a post or standard, B, an arm, C, projecting from the top of which supports the upper end of a vertical shaft, D, the lower extremity of which revolves in a suitable bearing, a. This shaft D carries two circular plates, E, F, in suitable bearings, in which revolve the journals of the swinging frames G, which carry the bobbins b upon which the strands c are wound. The short cranks d, which are attached to the ends of the journals of the swinging frames G, have their journals in a circular plate or ring, H, which fits over an eccentric, I, the hollow shaft of which fits over the shaft D, and carries a pulley, e, over which passes a band, f, which passes over the pulleys g h, and over a pulley, i, seen dotted in fig. 2, secured to the shaft D, so that as this shaft D is revolved by gearing connected with the driving-shaft J, the pulley e, with its eccentric, is revolved in an opposite direction, so as to cause the bobbin-frames G to turn on their axes, and thus give the required twist to the strands as they are being formed into rope in a manner similar to that described in our aforesaid Letters Patent of 1854; but as this forms no part of our present invention, it will not be further described. The rope j, after being laid, passes over the pulleys k l to the pulley K, around which it is wound several times, and this pulley is revolved at the requisite speed by a series of gears, L, connected with the driving-shaft. The rope is then led over the pulleys m n o to the

crane M, which consists of a straight, horizontal bar, 6, and a vertical bar 7, which is pivoted to a standard p, so that the bar 6 will swing freely in a horizontal direction. The rope is led from the pulley o over the pulleys q r s t of the crane M, and over a guide-pulley, N, to the winding or take-up reel O, which is revolved by means of a friction-wheel, P, connected with the gearing L. The guide-pulley N is provided with a hollow shaft, w, fig. 1, which slides freely on a horizontal shaft or rod, Q; secured between the standards R, and parallel with the axis of the reel O; and it will be seen that as the rope is wound up on the reel O, the guide-pulley N will be moved horizontally on the shaft Q, the crane swinging with it at the same time, thus insuring the rope being always drawn from the pulley to the reel in a line at right angles to its axis, without regard to the portion of the reel on which it is being wound, thus preventing all liability of the coils riding up on each other, and insuring their being laid on the rail with uniformity and regularity. This device is simple, and not liable to get out of order, while the cost of applying it is very trifling.

We will now proceed to describe the manner in which the regular and equal delivery of the strands e is effected. v, fig. 4, are rolls or short cylinders, of equal diameter, which revolve on hollow vertical shafts w, forming prolongations of the journals of the bobbin-frames G, and each of these rolls v carries a gear, y, which engages with a central gear, S, which revolves loosely on the shaft D, by which means the rolls v are prevented from revolving independently of each other; and these rolls are held in place on the shafts w by means of bent guide-pieces a', screwed on to their upper ends, as seen in figs. 2 and 4. The strands e are led from the bobbins up through the hollow shafts w, and down over the grooved portions 8 of the bent guide-pieces a' to the rolls v, around which they are wound five or six times to prevent them from slipping, and are thence led up over the grooved portions 9, and through the openings in the cross-bars 10 to the point where the rope is being "laid." And it will thus be seen that as the strands e are wound around the rolls v a sufficient number of times to prevent them from slipping, and as the rolls are of the same diameter, and are all caused to revolve simultaneously at an equal speed by means of the gears above described, the regular and equal delivery of the strands is insured as required to form perfect work, and the rolls v being placed above the plate E, are always in a convenient and accessible position. b' are rings, the under sides of which are inclined at 11 12, so as to form fleeters, and these fleeters are applied to the rolls v so as to cause the strands to be wound up regularly thereon, and prevent the coils from riding up on each other as the rolls are revolved. The fleeters b', which fit loosely on the rolls v, are kept in place and prevented from revolving with them by projections 13, which rest against the guide-pieces a', and, as an incline is formed on each side of the projection 13, the strands may be wound around the rolls, either to the right or the left, as may be desired.

Claim.

What we claim as our invention, and desire to secure by Letters Patent, is—

The sliding guide-pulley N, in combination with the crane M and the winding-reel O, operating substantially as described for the purpose set forth.

We also claim the rolls v, so arranged as to revolve simultaneously, in combination with the fleeters b' and the guide-pieces a', or their equivalents, for the purpose of insuring the equal delivery of the strands, substantially as described.

STEPHEN BAZIN,
JAMES A. BAZIN.
